UNITED STATES PATENT OFFICE.

HOLROYD FITZWILLIAM WAY, OF OREGON CITY, OREGON.

INCANDESCENT-LAMP-PROTECTING DEVICE.

1,345,466.

Specification of Letters Patent.

Patented July 6, 1920.

Application filed June 5, 1919. Serial No. 301,909.

To all whom it may concern:

Be it known that I, HOLROYD F. WAY, a citizen of the United States, and a resident of Oregon City, in the county of Clackamas and State of Oregon, have made certain new and useful Improvements in Incandescent-Lamp-Protecting Devices, of which the following is a specification.

My present invention relates generally to incandescent lamp protecting devices, and more particularly to means in connection with incandescent lamps and their sockets to prevent theft or unwarranted removal and reuse of an incandescent lamp in another socket.

More especially my invention has to do with what are known as weather-proof type of incandescent lamp sockets used in factories, and its object is the provision of certain means whereby an incandescent lamp utilized with a socket of this type may be rendered inoperative for use with the ordinary type of socket, or with a weather-proof socket unequipped with my improvements.

In the accompanying drawings illustrating my present invention:

Figure 1 is a vertical sectional view illustrating the practical application of my improvements;

Fig. 2 is a cross section taken substantially on line 2—2 of Fig. 1;

Fig. 3 is a detail perspective view of the clamping ring, and,

Fig. 4 is a detail side elevation of the connecting screw of the bulb collar removed.

Referring now to these figures I have shown in Fig. 1, a weather-proof type of lamp socket generally indicated at 10, in which the threaded base 11 of a bulb 12 is usually directly screwed, and insertable and removable therefrom as freely as with any other type of lamp socket.

As proposed by my invention, however, an insulated collar 13 is secured externally of and around one end of a threaded tube 14, the opposite end of which screws into the threaded lining 15 of the socket 10 until the collar 13 abuts the body of the socket around its open end. The external diameter of this collar 13 is approximately the same as that of the socket 10, as particularly seen in Fig. 1, and its external face has an annular rib, which coincides with the ribs usually to be found around the external open end of a weather proof socket, for the reception of a

retaining band or ring 16 shown in detail in Fig. 3, and provided with flanged edges 17 which engage over the ribs of the socket and the collar 13.

One end of the connecting ring or band 16 has a transverse slot 18, and the other end has an extending tongue 19 to be passed through the slot and bent back in reverting relation and soldered or otherwise secured to the ring or band in order to form a lock 60 which, after being secured in place, prevents removal of the collar 13 and the threaded tube 14.

That portion of the threaded tube 14 within and adjacent to the collar 13 is of such 70 diameter as to receive a relatively short threaded tube, one end of which is securely fastened within a collar 20 similar in size and shape to the collar 13, before mentioned, the tube 20 of the collar 21 being in turn of 75 sufficient diameter to receive the threaded base 11 of a lamp bulb 12 within the same.

As seen in Fig. 2, moreover, the tube 21 has an opening registering with the inner reduced end of a threaded opening extending 80 tangentially within its collar 20, the outer end of the opening of which collar communicates with a counter-bore 22, and is thus adapted for the reception of a locking screw 23 having a polygonal head 24 at one end 85 and a tapering threaded engaging portion 25 at its opposite end the latter of which works through the opening of the tube 21 and is adapted to bite into the material of the threaded base 11 of the lamp bulb so as 90 to securely fasten the base of the lamp bulb within the tube 21, and its collar 20, it being noted from Fig. 1 in particular that the opposite end of the tube 21 projects materially beyond the free or contact end of the lamp 95 base 11 so as to render the latter inoperative within the socket of ordinary construction unless equipped with my improvements.

That end of the first mentioned tube 14 opposite its collar 13, and which is designed 100 to screw within the lining 15 of the socket 10, is closed at its extremity by an internal insulated plug 26 supporting an axial electrode or contact stem 27, the outer end of which is engageable with the axial contact 105 28 of the socket 10, and the inner end of which projects to such a point as to be engageable by the axial electrode or contact stem 29 of the lamp base 11 when the tube 21 containing the lamp base is screwed 110

within the outer portion of the tube 14, until the collar 20 abuts the collar 13.

Thus the axial electrode or contact stem 27 extends to such a point as to enable the lamp base 11 to make proper contact with my construction, although if removed from the tube 14 it could not be screwed in the ordinary socket and make contact, while the tube 21 and the collar 20 are connected 10 thereon.

In order that the lamp base 11 may be prevented from being screwed out of the tube 21, the polygonal head 24 of the locking screw 23 which in the operative position extends 15 within the counter bore 22, as shown in Fig. 2, may be made of various forms so as to require different characters of socket wrenches for its rotation, and I am thus able to lock the lamp base within its tube in such 20 manner as to prevent its removal with any pull except the one designed for coöperation with its particular locking screw.

In the use of the invention, renewal lamps 25 will be provided, each with its tube 21 and collar 20, the former extending beyond the free end of the lamp base so that in case of a burnt-out lamp the old bulb may be quickly unscrewed with its tube and collar from the tube 14 screwed into the lamp 30 socket and a new one substituted.

I claim:—

1. The combination with a lamp socket and an incandescent lamp, the interior of which socket and the base of which lamp 35 are threaded for relative engagement, of a threaded tube into one end of which the lamp base is screwed having a collar around its said end and having its opposite end extending beyond the free end of the lamp base, to prevent engagement of its contact 40 with the socket contact, means for locking the said collar and the said tube in connection with the lamp base, and a threaded tube having its inner end screwed into the lamp socket, and having its opposite end 45 projecting therebeyond, said lamp tube being freely turnable into and out of the socket tube and said socket carried tube having a central electrode to engage at its opposite 50 ends, the spaced contacts of the lamp, socket and the lamp base.

2. The combination with a lamp socket, and an incandescent lamp for engagement therein, a threaded tube, to screw within the 55 socket having a socket abutting collar at its outer end, a central electrode supported in said tube and insulated therefrom, means engaging the socket and said collar for securing said tube within the lamp socket to 60 extend at one end beyond the open end of the socket, a second tube around the lamp base and projecting at one end beyond the free end of the lamp base, said second tube being freely turnable into and out of the 65 extended end of the first tube, and means for

securing said second tube in connection with the lamp base.

3. The combination with a lamp socket, an incandescent lamp to screw therein, of a pair of relatively engaging threaded tubes 70 freely turnable into and out of one another, means to secure one of said tubes around the lamp base, to extend beyond the end thereof, whereby to prevent engagement of the lamp and socket contacts, means to secure the other of said tubes within and projecting from the lamp socket, and a central electrode supported in insulated relation within the last mentioned tube and arranged to extend between the spaced contacts of 75 the lamp socket and base.

4. The combination with a lamp socket, an incandescent bulb having a threaded base, of a threaded tube, one end of which receives the base of the lamp bulb and is provided 80 with a surrounding collar, means in connection with the collar for securing the same and the said tube to the lamp base, a second threaded tube, one end of which screws within the lamp socket and is provided with an 85 internally supported plug, an axial electrode supported by the said plug, a collar secured around the opposite end of the last mentioned tube at the open end of the lamp socket, and means for securing said last 90 95 mentioned collar to the lamp socket, all for the purpose described.

5. The combination with a lamp socket, an incandescent bulb having a threaded base, of a threaded tube, one end of which receives the base of the lamp bulb and is provided 100 with a surrounding collar, means in connection with the collar for securing the same and the said tube to the lamp base, a second threaded tube, one end of which screws within the lamp socket and is provided with an internally supported plug, an axial electrode supported by the said plug, a collar secured around the opposite end of the last 105 mentioned tube at the open end of the lamp socket, means for securing said last 110 mentioned collar to the lamp socket, said last named means including annular ribs carried by the lamp socket and the said collar, and a flanged connecting band or ring 115 extending around the adjacent portions of the lamp socket collar and embracing the said ribs, said band or ring having its ends securely fastened as described.

6. The combination with a lamp socket, an 120 incandescent lamp, an extension tube for the lamp socket secured therein and projecting therefrom, a central electrode supported within the said tube, and insulated therefrom, a collar around the outer end of the 125 said tube, a second tube for engagement at one end within the outer end of the first tube, said second tube receiving the lamp base at its opposite end, a collar around the latter end of the second tube, and a clamping 130

screw threaded through the said collar and provided with a tapered threaded inner end to extend into engagement with the lamp base.

- 5 7. The combination with a lamp socket, an incandescent lamp, an extension tube for the lamp socket secured therein and projecting therefrom, a central electrode supported within the said tube, and insulated therefrom; a collar around the outer end of the said tube, a second tube for engagement at one end within the outer end of the first tube, said second tube receiving the lamp

base at its opposite end, a collar around the latter end of the second tube, and a clamping screw threaded through the said collar and provided with a tapered threaded inner end to extend into engagement with the lamp base, said last mentioned collar having a counter bore at the outer end of its threaded aperture, and said clamping screw having a polygonal head to extend within the counter-bore when the screw is in operative position, for the purpose described. 15
